MOLDED AIRFOIL, ESPECIALLY FOR
SUSTAINING ROTORSAgnew E. Larsen, Jenkintown, Pa., assignor to
Autogiro Company of America, Philadelphia,
Pa., a corporation of Delaware

Application February 27, 1942, Serial No. 432,544

2 Claims. (Cl. 244—123)

This invention relates to molded airfoils.

While some of the broader aspects of the invention are applicable to airfoils generally, the invention is particularly concerned with rotative airfoils, and more especially with the blades of aircraft sustaining rotors. Sustaining rotor blades are customarily of considerable length and, therefore, give rise to special problems of structure and operation resulting, for instance, from the high centrifugal forces set up in operation.

One of the primary objects of the invention is the provision of a blade which may readily and economically be molded, rather than built up of many pieces, as has been customary in the practice of the prior art.

In general, according to the preferred practice of the present invention, the blade is composed of two portions, one portion constituting a longitudinal strength structure having blade mounting means associated therewith, and the other constituting the molded material which is mounted on and secured to the strength structure and defines the airfoil contour of the blade.

Special features of construction of both of the major parts of the blade are provided for in accordance with the present invention, in order to meet a variety of different problems and requirements, all as will more fully appear hereinafter.

More specifically, it may be pointed out that the invention has in view making possible and practicable the molding of rotor blades from cellular, and preferably resilient, material of the general nature of "expanded" or sponge rubber. Many such materials, having varying degrees of resilience, elasticity and porosity are commercially available and may be used in accordance with the present invention, although it may be mentioned that in the preferred practice the material selected is appreciably expanded so as to provide considerable voids, and further has at least that degree of resilience which will avoid damage to the structure under the influence of the normal flexing and deformation of the blade which occurs in operation.

By the employment of molded cellular material, lightweight construction is secured, and the total quantity of material used is kept at a minimum.

How the foregoing and other objects and advantages are attained will appear more fully from the following description, referring to the accompanying drawings, in which—

Figure 1 is a fragmentary perspective view of a blade constructed in accordance with this invention and more particularly illustrating the blade section;

Figure 2 is a plan view, on a reduced scale, of a part of the blade of Figure 1, the central portion and tip of the blade being broken away;

Figure 3 is a view similar to Figure 1 but illustrating a modified blade;

Figure 4 is a view similar to Figure 2 illustrating the construction of Figure 3;

Figure 5 is a fragmentary plan view of still another form of blade, with intermediate and tip portions broken away;

Figure 6 is a fragmentary sectional view, on an enlarged scale, taken as indicated by the line 6—6 on Figure 5;

Figure 7 is a view similar to Figure 1 but taken generally as indicated by the line 7—7 on Figure 6; and

Figure 8 is a detail view of one part employed in the form illustrated in Figures 5 to 7.

In connection with Figures 2, 4 and 5, it may be mentioned that the break in each of these views represents the omission of the major portion of the blade length since, in most instances, sustaining rotor blades have a length of the order of twelve to fifteen times the chord dimension.

25 The blade of Figures 1 and 2 comprises a longitudinal strength structure taking the form of a tubular metallic spar 9 extended preferably substantially throughout the entire length of the blade. At the inner end of the spar a fitting 10 is provided, having an apertured lug 11 by means of which the blade may be pivotally connected to a rotative hub. Preferably, the blade mounting includes at least a "flapping" pivot providing freedom for movement of the blade transverse its mean rotative path of travel, and also a "drag" pivot (which may cooperate with lug 11) providing freedom for movement of the blade fore and aft within its general path of rotation. Since such pivots form no part of the present invention 40 per se, only brief reference is made thereto.

The blade is preferably built up by initially forming upper and lower blade sections 12 and 13, adapted to interfit at mating surfaces lying generally in the mean plane of the blade. Each 45 section is molded of cellular material and is provided with an elongated groove or recess adapted to fit the spar 9. When assembled, the two sections preferably define the complete airfoil contour of the blade, the sections being joined at the junction line 14 in the manner described more fully hereinafter.

It may be noted that Figure 2 illustrates the spar 9 as laid in the spar recess of the lower section 13 of the blade.

50 As will be observed from inspection of Figure 1, the outer surface layer 15 of the molded cellu-

lar material is denser (preferably less cellular) than interior portions of the blade, this denser layer being indicated by heavier stippling. Similarly, a denser layer 16 occurs immediately adjacent to the spar 9, and in the preferred practice these dense layers 15 and 16 merge, or at least come very close to each other, above and below the spar 9. This is of advantage in contributing to the strength of the cellular molded material.

A dense section 17 is also provided at the nose of the blade, and another similar section 18 at the trailing edge, these dense nose and trailing edge regions acting somewhat in the manner of nose and trailing edge stringers for stiffening and reinforcing the blade. The nose region 17 has the further object and advantage of maintaining the sectional center of gravity of the blade well forward, which is of importance for aerodynamic reasons which need not be considered herein.

In accordance with the preferred practice, all of the dense portions of the cellular molded material (15, 16, 17 and 18) are provided by curing or heat treatment, such as vulcanizing, this heat treatment process being effected in a manner to at least partially eliminate the voids in the surface layers and in the nose and trailing edge strips. In this way, not only the strength of the blade is enhanced but, in addition, a smooth exterior surface is provided. The surface may be finished by application of suitable weather-proofing dope or paint. Alternatively, fabric may be applied to the surface in a manner discussed hereinafter in connection with the third form of blade disclosed.

With reference to the attachment of the molded sections 12 and 13 to each other and to the spar, I prefer to employ "bonding" for this purpose. With vulcanizable materials, the blade sections 12 and 13 may be directly bonded to the exterior metal surface of the spar by a vulcanizing or heat treatment. When doing this, the outside surface of the spar is desirably initially brass or copper plated. Similarly, the two sections of the blade may be directly vulcanized to each other at their mating surfaces.

Bonding may also be achieved by the use of adhesives either at the mating surfaces of the two sections of the blade, or at the spar, or both.

In any event, the bonding of the molded material to the spar throughout the length thereof is highly advantageous from the standpoint of transmitting the centrifugal loads from the molded material to the spar and from there through the root end mounting to the rotor hub. The bonding may also serve to secure the molded material to the spar in torsion.

If desired, collars 19, having flanges or partial ribs 20, may be secured to the spar at spaced intervals, as indicated in Figure 2, and fitted or embedded in the molded cellular material to further enhance the keying of the blade proper to the spar.

Many features of the arrangement of Figures 3 and 4 are similar to those described above. Here, however, the spar takes the form of an elliptical tube 21 and each of the blade sections 12a and 13a is provided with a series of recesses 22 to the rear of the spar, the recesses being separated by bulkheads 23. The recesses and bulkheads of each blade section are located so as to register when the two sections are brought together, thereby forming a series of cavities such as indicated at 24 in Figure 3, for lightening the trailing edge portion of the blade.

In this form of construction, the collars 19a

carried by the spar are provided with flanges or partial ribs 20a projecting rearwardly therefrom a greater distance than in Figure 2, each of these flanges 20a desirably projecting part-way into a bulkhead 23 for reinforcement thereof.

Ports 25 in the bulkheads serve to interconnect the several cavities 24, and provision is made for venting these spaces, as through a vent 26, located adjacent the tip of the blade. Undesired build-up of pressure within the cavities 24 toward the outboard end of the blade under the action of centrifugal force is thereby avoided.

The blade structure of Figures 5 to 8 inclusive is also built up on a longitudinal strength structure, taking the form of an elliptical step-tapered spar 27 of the general type shown in patent of Paul H. Stanley and Agnew E. Larsen, No. 2,272,439 granted February 10, 1942.

One of the primary differences between the blade here shown and those previously described is that the blade is molded in sections adapted to be arranged in a series lengthwise of the blade, each section defining the full cross sectional contour of the blade. Figure 6 illustrates portions of blade sections 28 and 30, and also the intermediate section 29 in full, and from examination of this view it will be seen that each section is provided with an aperture adapted to receive the spar 27, the several sections being serially threaded onto the spar.

A further distinguishing characteristic of the blade of Figures 5 to 8 is the fact that outboard sections of the blade are of diminishing thickness, corresponding somewhat to the taper steps of the spar 27. As shown in Figure 5, the plan form of the blade as a whole may also be tapered toward the outboard end of the blade.

It is contemplated that each section of the blade here shown shall be molded of material in accordance with the description of Figures 1 to 4 inclusive, although these sections are desirably molded as units, rather than formed of upper and lower mating halves.

In building up the blade of Figures 5 to 8, the inboard end section is first threaded onto the spar from the outer end thereof, after which a rib 31 is threaded onto the spar and secured in position so as to transmit the load of centrifugal force from the inboard molded section to the spar. This procedure is followed for each successive section of the blade, working outwardly toward the tip. The rib 31 is provided with a flange 32 or other suitable means for welding or other attachment to the spar.

When all sections of the blade are assembled on the spar, junction strips 33, for instance of rubberized fabric, may be applied to join the mating surfaces of adjacent sections and provide a smooth exterior surface. Following this, a fabric covering 34 may be applied and doped in place. In applying the fabric covering (which, as before indicated, may also be used in the blades of Figures 1 to 4 inclusive) adhesive or dope may be relied upon for securing the fabric in place or, if desired, heat may be applied so as to embed the fabric directly in the surface layer of the molded material. It may be mentioned that this expedient may be employed as an alternative or in combination with the surface layer of increased density, in order to provide the desired strengthening, reinforcement and smoothness of the blade surface.

While the ribs 31 in the arrangement of Figures 5 to 8 may be the primary means relied upon for transmission of the centrifugal load from the

blade sections to the spar, even in this form the blade sections are also preferably bonded directly to the spar, as described above.

A ballast rod 35 may be threaded into apertures provided toward the nose of the blade sections for the purpose of maintaining the cross sectional center of gravity well forward.

I claim:

1. An aircraft sustaining rotor blade comprising a main longitudinally-extending metallic spar; a plurality of retaining members fixedly located on said spar at intervals along its length; a plurality of blade body members of molded homogeneous material, said body members having cavities abaft the spar and bulkheads separating the cavities, and said body members further being preformed to receive the spar, to engage the retaining members within the bulkheads, and to mate in abutting relationship; and an external covering of sheet material, said blade body members being mounted on said spar in abutting relationship and being secured by bonding as against relative movement of one member with respect to another, and being secured as against displacement lengthwise of the spar by said retaining elements, and being further secured as against disruptive forces, by being bonded to said sheet material in the region of the joints between abutting body members, said retaining members serving also as stiffening members for the blade

as a whole, and for the bulkheads lying between the cavities aforesaid.

2. An aircraft sustaining rotor blade comprising a main longitudinally-extending metallic spar; a plurality of retaining members fixedly located on said spar at intervals along its length; a plurality of blade body members of molded homogeneous material, said body members having cavities abaft the spar and bulkheads separating the cavities, and said body members further being preformed to receive the spar, to engage the retaining members within the bulkheads, and to mate in abutting relationship, and an external covering of sheet material, said blade body members being mounted on said spar in abutting relationship and being secured by bonding as against relative movement of one member with respect to another, and being secured as against displacement lengthwise of the spar by said retaining elements, and being further secured as against disruptive forces, by being bonded to said sheet material in the region of the joints between abutting body members, said retaining members serving also as stiffening members for the blade as a whole, and for the bulkheads lying between the cavities aforesaid, in which structure means are provided for venting adjacent cavities lengthwise of the blade and for venting the outermost cavity to the atmosphere.

AGNEW E. LARSEN.
